CLAIM

I claim the ornamental design for a slot table hybrid design, as shown and described.

DESCRIPTION

FIG. 1 is a front perspective view of a slot table hybrid design showing our new design;

FIG. 2 is a top view of the slot table hybrid design shown in FIG. 1;

FIG. 3 is a front view of the slot table hybrid design shown in FIG. 1;

FIG. 4 is a back view of the slot table hybrid design shown in FIG. 1;

FIG. 5 is a side view of the slot table hybrid design shown in FIG. 1;

FIG. 6 is a front perspective view of a slot table hybrid design showing a variation of our new design;

FIG. 7 is a top view of the slot table hybrid design shown in FIG. 6;

FIG. 8 is a front view of the slot table hybrid design shown in FIG. 6;

FIG. 9 is a back view of the slot table hybrid design shown in FIG. 6; and,

FIG. 10 is a side view of the slot table hybrid design shown in FIG. 6.

The broken lines are included for the purpose of illustrating portions of the “article” and form no part of the claimed design.

1 Claim, 10 Drawing Sheets
